(57) **CLAIM**

The ornamental design for a guitar with tremolo, as shown and described.

DESCRIPTION

FIG. 1 is a top, left, front perspective view of a guitar with tremolo showing my new design;

FIG. 2 is a top, right, rear perspective thereof;

FIG. 3 is a top view thereof;

FIG. 4 is a bottom view thereof;

FIG. 5 is a front view thereof;

FIG. 6 is a rear view thereof;

FIG. 7 is a left side view thereof;

FIG. 8 is a right side view thereof;

FIG. 9 is an enlarged view of the portion taken at line-9 in FIG. 3;

FIG. 10 is an enlarged view of the portion taken at line-10 in FIG. 2; and,

FIG. 11 is an enlarged view of the portion taken at line-11 in FIG. 4.

The evenly spaced broken lines represent the portions of the design that form no part of the claim.

The dot-dashed broken lines denote the enlarged portions of the design and form no part of the claim.

The guitar with tremolo is shown with a symbolic break in its length along the neck. The appearance of any portion of the article between the break lines forms no part of the claimed design.
